WEFT FEELER MECHANISM FOR LOOMS

Zdeněk Sochor, Dvur Kralove n. L.,
CzechoslovakiaApplication January 29, 1937, Serial No. 123,079
In Czechoslovakia January 29, 1936

3 Claims. (Cl. 139—269)

This invention relates to weft feeler mechanism for looms, and it consists in the constructions, arrangements and combinations herein described and claimed.

5 Preferably shuttle or bobbin changing for weft replenishing in looms, requires a feeler mechanism for bringing the shuttle or bobbin changing motion into action when the weft in the shuttle is exhausted. Such feeler mechanism should be of 10 a character not likely to damage the weft by mechanical, electrical or other action and should be of simple construction, reliable, and require only a minimum of attention.

Many of the feeler mechanisms in use are of 15 such construction that the feeler device is constantly in motion and the feeler actually collides with or encounters the weft in the shuttle at every beat-up of the sley. When the weft is nearly exhausted, then the feeler device remains stationary during the beat-up and this condition 20 brings about the automatic shuttle or bobbin change.

Thus a more or less complicated movement of 25 mechanical parts involving some weight occurs, about 700 times and initiated by mechanical 30 encounter with the easily damaged weft, the change as stated being commonly brought about by non-movement of feeler mechanism.

A considerable number of feeler mechanisms 35 act in such a way that the weft is felt by the actual feeler entering into the shuttle box at a height coinciding with the longitudinal centre of the shuttle in the shuttle box. Such a construction of feeler mechanism is not well suited for certain 40 automatic looms of the drop-box type where the weft requires to be felt in the shuttle box at the plain end of the loom.

The movement of the feeler mechanism during 45 ordinary running of the loom is so slight as to be hardly noticeable, and such movement is restricted by a lever or the actual feeler mounted on the mechanism proper. Only once in approximately 50 700 beat-ups of the loom does the whole feeler mechanism move, that is, when an automatic change of shuttle or bobbin is required. Accordingly, damage to delicate weft is prevented and wear and tear on the feeler mechanism is minimized.

A feeler mechanism according to the invention 55 can be safely used in cases where a length of weft is present between the shuttle and the wall of the shuttle box, because the actual feeler does not operate at a level coinciding with the longitudinal center of the shuttle in the shuttle box, but above or below that level and preferably above.

The whole feeler contrivance is mechanically very simple and no auxiliary source of energy such as electricity is necessary. Also, the movement of the actual feeler during weaving only amounts to the swing of the end of said feeler through an arc of a fraction of an inch and so possibility of damage to the weft is reduced. 5

The feeler is set or regulated to act at the moment when the weft on the bobbin is sufficiently exhausted and according to requirements 10 of the particular type of loom.

The feeler contrivance consists of a small smoothly shaped pivoted lever and its sliding support, springs, etc. and is mechanically very simple, which is an advantage for the working conditions 15 of a weaving shed.

The invention is illustrated by way of example in the accompanying drawing, wherein

Figure 1 is a view of the weft feeler mechanism partly in section with the sley in forward position. 20

Figure 2 shows a plan view of Figure 1.

Figure 3 is a back view of the mechanism shown in Fig. 2.

Figure 4 is a view similar to Figure 1, but with the actual weft feeler down following exhaustion 25 of weft.

The cop bobbin 2 with its wound-on weft engages the skewer of the shuttle in such a way that a cut-out cavity 1 in the base or butt of the said bobbin presents a horizontal face and an upright 30 abutment as shown in Figures 1 and 2. The position of the horizontal face is assured by reason of a pin 34 on the skewer of the shuttle engaging a horizontal bore or cavity 3 in the base or butt of the bobbin. The front wall of the shuttle 33 is 35 provided with an entrance slot 32 opposite the cut-out cavity 1 at the base of the cop bobbin.

The feeler contrivance is mounted to the fixed framing of the loom in front of the breast beam by means of a support 18. An adjustable bracket 40 45 15 is fixed to the support 18 by screws 17. The supporting structure 13 for the feeler contrivance is adjustably fixed to the bracket 15 by screw 14 and can be adjusted horizontally nearer or further relatively to the front end portion of the sley. A 45 slide 10 is movable in a square guide sleeve 12, and this slide 10 is pressed towards the front wall of the sleeve 12 by means of a spiral spring 11 or equivalent means. The forward movement of slide 10 is limited by a split pin 16. The sleeve 12 50 has a slot in the base for a cam 9 which projects downwardly from the slide structure 10. A crank rod 6 which is attached to the slide structure 10 is provided with a shaft upon which the actual feeler 5 is pivoted. This feeler 5 by reason of its 55

weight or under the influence of a spring 7, tends to assume a horizontal position as indicated in Figure 4. A rearward extension of the feeler 5 rests against a stop 8.

5 A lever 24 is provided adjustably supported in a drum 22, which is accomplished by passing the lower free end of the lever through an aperture formed in the drum, the lever being secured in the aperture by a set screw 23. The aperture receiving the lever 24 is off center, and a lever 25 is similarly secured upon the drum 22. The drum 22 is oscillatably mounted upon an axle 20 carried by a depending arm 19 of the bracket 15 a spring 21 secured upon the axle 20 and having an end in engagement with the lever 25 tends to hold the cam 9 in engagement with the lever 24 as required during weaving.

The lever 25 extends in a direction opposite the lever 24 and terminates in an angularly disposed stud upon which there is revolutely mounted a roller 26, adapted to engage and press a lever 27 into engagement with a pin 29 carried by a weft fork hammer 30. The lever 27 has a tooth 28 adapted to be engaged by the pin 29 imparting a movement to the shaft 27 corresponding to the movement of the hammer. This movement starts the automatic shuttle or bobbin change.

The mechanism acts in the following way:

30 When the sley is drawn up or in its forward position, feeler lever 5 projects into the shuttle above the line of the horizontal axis of the bobbin and is slightly forward or over the longitudinal center of the shuttle when the sley is fully 35 up to the breast beam (see Fig. 1), this being possible because the front wall of the shuttle box is provided with a slot for the purpose, as is the front wall of the shuttle. The disposition of feeler lever 5 is so adjusted that it does not pass wholly 40 above the bobbin, but its forward end encounters the wrapped-on weft and so the feeler lever 5 is gently deflected into an inclined position and rests or is supported on the weft, bridging the cut-out cavity 1 at the base or butt of the bobbin 45 when the sley is in its extreme forward position (see Fig. 1). When the sley moves back, the feeler 5 returns to its normal horizontal position.

When the weft on the bobbin is exhausted, there 50 is nothing to direct and keep feeler 5 deflected and so it encounters the vertical wall of the cut-out cavity 1. As a consequence, when the sley next moves forward, the slide 10, in connection with which the feeler 5, is pushed back against the action of spring 11. The result is, the cam 9 55 on the slide 10 is pushed back nearer to the fixed framing, releasing the arm 24 by the protruding cam 9 of the slide 10 and changes from the position seen in Figure 1 to the position seen in Figure 4 under action of the spring 21. As a result 60 of this, the second lever arm 25 with anti-friction roller 26 moves to its lower position shown in dotted lines, Fig. 3, thus effecting connection of

lever 27 with the weft fork hammer 30 thereby bringing about the desired automatic shuttle or bobbin change. At the proper time, lever 25 is lifted by the aid of a projection on lever 27 whereupon the slide 10 with protruding horn 9 returns into the original position as shown in Figure 1, and lever arm 24 is reset.

I claim:

1. A mechanical weft feeler mechanism for looms comprising a sley, a cop bobbin having a cavity in the form of a tangential notch, the longer side of which is in a substantially horizontal plane, the loom having a breast beam, a slide member supported by the breast beam, a spring-urged feeler element carried by the slide, a spring means urging the slide in the direction of the cop bobbin, said feeler member being in tangential contact with the weft on the bobbin but movable into the tangential notch upon exhaustion of the weft, whereby said slide will partake of forward movements of the sley thereby actuating mechanism for effecting change of the cop bobbin.

2. Mechanical weft feeler mechanism for looms comprising a sley, a shuttle, a cop bobbin therein having a tangential notch, the longer side of which is disposed in a substantially horizontal plane, the loom having a breast beam, a sleeve fixed to the beam, a slide within the sleeve, spring means urging the slide in the direction of the sley, a spring-urged feeler element carried by the slide, the free end of the feeler element being in tangential contact with the weft on the bobbin and movable into the tangential notch upon exhaustion of the weft, whereby the slide will partake of forward movement of the sley, cop change mechanism including a weft fork hammer, a shaft actuated thereby, a pair of hingedly connected levers, one of said levers being positioned in proximity to the shaft, the other of said levers being disposed beneath the slide, a cam on the slide normally contacting the last named lever, and spring means connected between the levers urging the last named lever into bearing contact with the cam.

3. A mechanical weft feeler mechanism for looms comprising a sley, a shuttle, a cop bobbin therein having an angular tangential cavity, a feeler element comprising a pivoted lever projected through the shuttle in the direction of the warp, the feeler element contacting the weft tangentially above the longitudinal axis of the shuttle and being of a character to be deflected so long as the weft supply remains and upon exhaustion of the weft supply, said lever being of a character capable of automatic deflection and movable to a substantially horizontal position to engage the cavity of the cop bobbin, whereby the feeler will partake of forward movement of the sley to actuate cooperating mechanism for effecting the cop change.

ZDENEK SOCHOR.
